Specification for Design.

Patented Apr. 28, 1914.

Application filed February 3, 1914. Serial No. 816,328. Term of patent 14 years.

To all whom it may concern:

Be it known that I, VERNE WILLIAMS CLISBY, a citizen of the United States, residing at Wellington, in the county of Lorain and State of Ohio, have invented a new, original, and ornamental Design for a Cooking-Utensil Body, of which the following is a specification, reference being had to the accompanying drawing, forming part thereof.

Figure 1 is a plan view, and Fig. 2 is a side-elevation of a cooking-utensil body, showing my new design.

I claim:

The ornamental design for a cooking-utensil body, as shown.

VERNE WILLIAMS CLISBY.
